US00D894248S

(12) **United States Design Patent** (10) **Patent No.:** **US D894,248 S**
(45) **Date of Patent:** **** Aug. 25, 2020**

(54) **ROBOT**

(71) Applicant: **ROBORUS Co., Ltd.**, Seoul (KR)

(72) Inventors: **Dae Hoon Kim**, Seoul (KR); **Sang Ki Lee**, Yongin-si (KR)

(73) Assignee: **ROBORUS CO., LTD.**, Seoul (KR)

(**) Term: **15 Years**

(21) Appl. No.: **29/662,173**

(22) Filed: **Sep. 4, 2018**

(30) **Foreign Application Priority Data**

Aug. 31, 2018 (KR) 30-2018-0040641

(51) **LOC (12) Cl.** **15-99**

(52) **U.S. Cl.**

USPC **D15/199**

(57) **CLAIM**

The ornamental design for a robot, as shown and described.

DESCRIPTION

FIG. 1 is a perspective view of the robot showing my design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings depict portions of the robot that form no part of the claimed design.

1 Claim, 7 Drawing Sheets
